UNITED STATES PATENT OFFICE.

WESLEY E. KEESEE, OF HUNTINGTON PARK, CALIFORNIA.

DESIGN FOR A COMBINED LUBRICATING OIL AND GASOLINE DISPENSING APPARATUS.

Application filed June 6, 1922. Serial No. 2,550. Term of patent 7 years.

To all whom it may concern:

Be it known that I, WESLEY E. KEESEE, a citizen of the United States, residing at Huntington Park, in the county of Los Angeles and State of California; have invented a new, original, and ornamental Design for a Combined Lubricating Oil and Gasoline Dispensing Apparatus, of which the following is a specification, reference being had to the accompanying drawing, forming a part thereof.

The figure is a side elevation of a combined lubricating oil and gasoline dispensing apparatus, showing my new design.

I claim:

The ornamental design for a combined lubricating oil and gasoline dispensing apparatus, as shown.

WESLEY E. KEESEE.
